[57] CLAIM

The ornamental design for a voice communication module for use with computers, as shown and described.

DESCRIPTION

FIG. 1 is a perspective view of a voice communication module for use with computers showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.
